STRIP SHINGLE

Joseph A. Murray, Bethesda, Md.

Application September 14, 1942, Serial No. 458,269

1 Claim. (Cl. 108—7)

This invention relates to strip shingles and particularly to strip shingles which, when laid, expose to the weather a plurality of shingle simulating tabs. The invention relates to the type of strip shingle which has a continuous lower edge and in which the tab is itself also a simulation produced by shadow effects.

A general object of the invention is to make possible the production of a strip shingle which is exceptionally pleasing on the roof, which presents at its lower edge a marked thick butt appearance and which can be laid better than many thick butt simulating shingles, all by utilizing a comparatively light and inexpensive base combined with materials ordinarily wasted. A particular object of the invention is to make possible the use of slate coated roofing waste, either in whole or in part, for producing the exposed faces of the tab simulating portions of the strip shingles.

Another object of the invention is to produce at a relatively low cost of manufacture strip shingles in which most desirable color effects can be obtained. Other objects and important features of the invention will appear from the following description and claims when considered in connection with the accompanying drawings in which—

Figure 1 shows a plurality of strip shingles of the present invention and the manner of laying them upon a roof;

Figure 2 shows a strip single embodying the present invention;

Figure 3 shows a simple method of manufacturing these shingle strips and also simple apparatus which may be utilized in practising the method.

In manufacturing the strip shingle of the present invention there is preferably utilized for the base of the strip an inexpensive asphalt-saturated ordinary felt or an asphalt-saturated asbestos felt of comparatively light weight, for example 15 to 30 pounds per square. Other similar water-proof fabric could also be utilized.

If the strip shingles are to be manufactured in the manner shown in Figure 3, and a 36" x 14" strip is desired, a 32" asphalt-saturated felt or similar material is preferably slit to form two 16" strips, each of which is preferably again rolled for convenience in handling.

As shown in Figure 3, the 16" strip 2 as it comes from the roll 4, mounted on the spindle 6, is passed between two draw rolls 8 and 10. Before the strip 2 enters the draw rolls it strikes a turning flange 12 which is shaped to turn over a

2" margin of the felt before it enters the rolls so that the rolls will fold it down and flatten it against the upper face of the felt. The strip 2 with its folded over edge 14 now passes to a coating mechanism which operates to coat both faces of the strip with asphalt. The coating mechanism shown comprises a lower roller 16 dipping into asphalt in a tank 18 and an upper roller 20 which is supplied with asphalt from an upper tank 22 having a feed spout 24 controlled by a valve 26. The asphalt used in coating the strip 2 may be either hot asphalt or cold emulsified asphalt. Hot asphalt is preferably used.

While the asphalt coating is still tacky, the 15 sheet is passed over a working table 28 where one or more workers place pieces of slate-surfaced, asphalt saturated and coated felt in position to form the tab-simulating portions of the strip shingle. These pieces, as above pointed out, 20 may be cut from roofing waste and each may be of a different color, if so desired, to produce desired color effects on the roofing. If sufficient waste does not accumulate to meet the demands for these tab simulating rectangular pieces it is 25 still an economical procedure to cut them from new material since only 75 square feet of such material will be used in providing a square of strip shingles embodying this invention as compared with 250 square feet of such material required to make a square of ordinary strip shingles.

The pieces employed to make the tab-simulating portions of the shingle strip for a strip shingle 36" long and 14" from top to bottom 35 may be of any suitable dimensions depending upon the desired exposure and head lap. For a 6" exposure and a head lap of 4", suitable dimensions of the pieces might be 5" x 8" and 5" x 7", using both on the same strip to give 40 variety.

These pieces of slate-coated material are preferably placed 1" apart along the strip and 1/2" up from the lower edge of the strip, a 2" margin of coated felt being left at the left hand end 45 of the strip and a 1" margin at the right hand end of the strip. If two 5" x 8" pieces and two 5" x 7" pieces are used, this will give for the length of the strip 2" plus 8" plus 1" plus 7" plus 1" plus 8" plus 1" plus 7" plus 1" equals 50 36".

The tile or tab pieces 30 having thus been placed in position on the strip, the strip is then passed through pinching rolls 32 and 34 which press the tab or tile pieces 30 into the asphalt to insure 55 proper adhesion, after which the surface is dusted

with talc or other suitable material for preventing sticking in piling. The duster is shown at 36. A shear 38 acts to cut the strips to the proper lengths.

As shown in Figure 1, if a strip be constructed in this manner with the tab or tile 30 at the right hand end one inch from the side edge of the strip, the strip may then be laid with a 2" side lap and a 4" head lap to give complete double coverage throughout the roof. The 2" side lap leaves an inch of the base surface exposed between the tile near the right hand edge of one strip and the left hand tile of the next strip in order to provide between these two tiles the deep contrasting shadow line essential to produce a simulation of individual shingles.

In laying a roof of strip shingles of the construction hereinabove described, the strips are laid in courses across the roof. The lower edges of the strips may be drawn back a sufficient distance from the course below to show a zone of the black underbody of the underlying strip to increase the shadow line of the butts, although this may not be necessary in view of the $\frac{1}{2}$ " margin between the lower edges of the tiles 30 and the lower edge of the strip. From the description of the process of making the strip it will be seen that the strip has already a substantial butt thickness so that with this shadow effect produced by the $\frac{1}{2}$ " margin or further emphasized by drawing the strip back slightly from the upper edges of the tiles 30 of the strip below there will be produced a marked thick butt effect as shown in Figure 1. The side lap, that is, 2" at the left hand edge of each strip is tucked under the strip to the left of it and can be cemented thereto if desired further to prevent any tendency of the strip to blow up. The fact that the area around the overlap is black facilitates this cementing since any slight smearing of the cement outside the overlap does not make a visible stain. Shingles or strips of this type are customarily nailed with two to three large head roofing nails so located in the black area above the tiles that the next strip above overlies the nails for at least 2".

Some of the advantages of the novel strip construction of the present invention have been pointed out hereinabove. Other advantages to which attention has not been particularly directed are the fact that the strip is quite markedly tapered, with a heavy butt and a lighter flexible under body, so that it tends to lie flatter in the roof and the successive strips conform to each other better than other types of strip shingles on the market. Furthermore, the tabs or tiles 30

give each tier a substantially continuous body thus preventing curling and blowing up. In addition, the deep shadow lines produce a massive appearance of the shingle tabs on the roof. With strips of the dimensions hereinabove described, as few as 70 strips are required for a roofing square.

Strips of this general construction can also be used as siding material to simulate brick walls. The relative thinness and flexibility of the under body of this strip, which permits the strip to conform more readily to the course below, especially suits this strip for use in simulating brick siding, since the rigidity of the underlying portions of other imitation brick sidings on the market often tends to force the butts to stand away from the walls, thus completely destroying the brick wall effect.

Although we have hereinabove referred to tile-like or rectangular pieces of slate-surfaced, asphalt coated and impregnated felt as constituting suitable material for use in making the imitation tabs and the expression "felt" has been used in the claim to define this material, it will be understood that the invention contemplates also the employment of any suitable substitutes for the asphalt-saturated and coated and slate-surfaced felt which may be available, particularly in the form of waste or scrap material.

What I claim as new is:

30 A strip shingle comprising a strip of relatively light unsurfaced waterproof material having a marginal edge portion thereof folded over to increase the butt thickness of the strip, a coating 35 of asphalt covering the strip, and rectangular pieces of previously slate surfaced, asphalt coated and impregnated felt of an up and down dimension approximating the strip shingle exposure dimension, said pieces being embedded in the asphalt coating in spaced relation to each other 40 along the butt edge of said strip to simulate tabs and to give an increased thick butt effect, said asphalt coating serving also to secure said folded over margin in its folded condition and at the same time to increase further the thick butt effect 45 and the rectangular piece at one end of the row of pieces being spaced from the side edge of the strip a distance equal to a tab spacing and the rectangular piece at the other end being spaced from the side edge to provide both for a substantial side lap and also for exposure of a portion 50 of the upper strip base between said end rectangular pieces.

JOSEPH A. MURRAY.
